F. B. COOK.
HEAT COIL.
APPLICATION FILED APR. 8, 1905.

Inventor:

UNITED STATES PATENT OFFICE.

FRANK B. COOK, OF CHICAGO, ILLINOIS.

HEAT-COIL.

No. 802,684.

Specification of Letters Patent.

Patented Oct. 24, 1905.

Application filed April 8, 1905. Serial No. 254,596.

To all whom it may concern:

Be it known that I, FRANK B. COOK, a citizen of the United States, residing at Chicago, in the county of Cook and State of Illinois, 5 have invented new and useful Improvements in Heat-Coils, of which the following is a specification, reference being had to the accompanying drawings illustrating same.

My invention relates to thermal protectors 10 for electrical circuits, my object being, first, to provide a protector in which the heat generated therein is concentrated and confined to the parts where it is to be utilized to operate the device, and, second, to provide a large 15 shearing-surface for the heat-susceptible material to give greater strength to the soldered connection when cool. To accomplish these ends, first, I reduce the size of certain heat-conducting elements leading from the heated 20 parts and leave an air-space surrounding the said heated parts as much as possible; second, I provide an enlarged end portion of the heated core, which affords a large surface for the heat-susceptible material; and, third, I employ 25 a compact heat-producing winding wound upon the heated core near the enlarged end portion thereof.

I will more particularly describe my invention by reference to the accompanying drawings, in which—

Figure 1 is a side elevation of the heat-coil of the invention. Fig. 2 is an end elevation of Fig. 1. Fig. 3 is a cross-sectional view of the heat-coil, taken on line A B of Fig. 1. Fig. 35 4 is a cross-sectional view of the heat-coil, taken the same as Fig. 3, showing portions thereof in a separated relation. Fig. 5 is a cross-sectional view of a modified form of the heat-coil, taken the same as Fig. 3; and Fig. 40 6 is a view showing the heat-coil in use as a protective device.

Like characters refer to like parts in the several figures.

The heat-producing winding o is wound upon 45 the heat-conducting core s in a compact manner and close to the enlarged end portion s^2 of core s . The enlarged portion s^2 is inserted into a hollow portion or cap r of end connection-terminal c , where it is normally secured 50 by a heat-susceptible material p . The heat-producing winding being thus concentrated near the heat-susceptible material, the heat generated therein is therefore applied direct to the soldered connection, which it unsolders. 55 This end of s is preferably concave, so as not to allow the heat-susceptible material p to

unite same to r on the flat end surface thereof, which surfaces would not separate by shearing when the device operates. The other end of core s is provided with a flat disk which is 60 securely held between the insulating-washers k and m , the latter preferably being a split washer. The end connection-terminal d is provided with a hollow cup-shaped portion n at the inner end thereof, which is formed 65 around the insulating-washers k and m and the interposed disk end of core s , so as to firmly hold the same therein. The inner portion n of end portion d is connected to the outer portion of d by a small neck h , which greatly reduces the conduction of heat from the heated 70 parts. The terminals of the winding o are preferably connected to the core s and the cup-shaped portion n , respectively. The end terminals c and d are provided with respective 75 grooves e and f therein, adapted to engage respective connecting-springs u and t . The inner portions of the heat-coil are inclosed by an insulating-shell b , which may be split and sprung on in place. 80

Springs t and u are provided with tongues t^2 u^2 , respectively, which are adapted to firmly hold the end connection-terminals d and c of the heat-coil in contact therewith. Line conductors w and x are connected to springs t and 85 u , respectively. Spring v is preferably connected to earth through conductor y . When the heat-coil operates, as shown in Fig. 4, spring u engages spring v , and thus grounds conductor x . This operation of the heat-coil 90 also breaks the circuit between conductors w and x .

Fig. 5 shows a modified form of the heat-coil in which the end connection-terminals d^2 and c^2 are connected to the inner parts of the 95 device by necks h^2 and c^2 , respectively. In this form of the invention the heat is more nearly confined to the inner portions of the device, as the heat-conducting paths to each end thereof are very small. 100

When an abnormally large current traverses the winding o of the heat-coil, it generates heat therein, and thus heats the core s . The core s conducts the heat from the winding o to the fusible material p , which secures 105 the hollow portion r to the surface s^2 of core s . When this heat is sufficient, the fusible material p softens, and as the device is held in a state of stress by springs t and u the end terminal c now separates from the core s , as 110 shown in Fig. 4. The neck h being small, very little heat is conducted to the end terminal d ,

where it would be wasted. The enlarged portion s^2 of core s is preferably large in diameter and short in length, so as to give a large external surface for s^2 and at the same time 5 provide a large clearance between the members s and c when they separate. If the enlarged portion s^2 were long, it would require a greater range of motion for spring u relatively to spring t to produce the same clearance 10 between the members s and c . The concave end of core s serves to compel the heat to be conducted through the fusible material p and not through the end surface of core s .

In Fig. 5 the end terminal c^2 separates from 15 the core s when the fusible material p softens in a manner similar to that described for end terminal c and core s . In this form of the invention little heat is conducted to either of the end terminals d^2 or c^2 , due to their respective 20 small heat-conducting connecting portions h^2 and c^2 .

The principal features of this invention are 25 the compact winding wound close to the fusible material, the enlarged shearing-surface for the fusible material, and the reduced portions through which the end connecting-terminals are connected to the inner parts of the heat-coil.

Having thus described my invention, what I claim as new, and desire to secure by Letters 30 Patent, is—

In a thermal protector for electric circuits, a core provided with enlarged cylindrical ends, a heat-producing winding wound upon the said core between the said enlarged ends, a cup-shaped portion in which one said enlarged end is normally secured by heat-susceptible material so that the two soldered parts may entirely separate when the heat-susceptible material is softened, a second cup-shaped portion in which the other said enlarged end is insulatively secured, suitable terminals for the protector, small neck-like portions connecting the said cup-shaped portions to the respective terminals, a suitable shell inclosing the device 45 from one terminal to the other, and an air-space between each cup-shaped portion and its terminal, inclosed by and within the said shell.

As inventor of the foregoing I hereunto subscribe my name, in the presence of two sub- 50 scribing witnesses, this 4th day of April, A. D. 1905.

FRANK B. COOK.
